UNITED STATES PATENT OFFICE.

ANDREW W. AITKEN, OF SPRINGFIELD, OHIO.

INTERNAL-COMBUSTION ENGINE.

Application filed June 28, 1922. Serial No. 571,414.

To all whom it may concern:

Be it known that I, ANDREW W. AITKEN, a citizen of the United States, residing at Springfield, in the county of Clark and State of Ohio, have invented certain new and useful Improvements in Internal-Combustion Engines; and I hereby declare that the following is a full, clear, and exact description thereof, reference being had to the accompanying drawings, which form part of this specification.

This invention relates to internal combustion engines, and its object is to provide such an engine with a continuous fuel gas intake passage produced by forming communicating ducts in the walls of the base or crank case, the cylinders, and the cylinder heads thereof, such passage conducting the fuel gases direct from the carburetor to the intake valves, and being heated by conduction of heat through the walls of the cylinders, whereby the fuel gases are kept hot, and condensation of the fuel gases in the passage is prevented. A further object of the invention is to do away with the ordinary manifolds and yet properly heat the fuel gases and prevent condensation thereof in the fuel intake passage.

This invention is particularly adapted for use with a four-cycle two-cylinder opposed type gasoline engine, without crank case compression; but may readily be adapted for use with other types of gasoline engines, if desired.

I will explain the invention with reference to the accompanying drawings, which illustrate one practical embodiment of the invention, to enable others to adapt and use the same; and summarize in the claims the novel features of construction and novel combinations of parts for which protection is desired.

In said drawings:

Fig. 1 is a diagrammatical longitudinal section through the crank case, cylinders, and cylinder heads of an internal combustion engine showing the novel construction and arrangement of the fuel intake passage therein, and the direct connection of the carburetor with said passage.

Fig. 2 is a side elevation of an engine having such novel fuel passage.

In the drawings, the invention is illustrated in connection with a four-cycle two-cylinder opposed type gasoline engine, hav-

ing a crank case 1, opposed cylinders 2, 2, and cylinder heads 3, 3.

The crank case 1 may be of any suitable kind, and shape, but is preferably rectangular, and is provided with suitable bearings 1^a for the crank shaft 1^b. In one side of the crank case, and preferably below the bearings of the crank shaft, is a fuel gas intake duct 1^d preferably formed in the casting of the crank case by placing suitable cores in the mold. This duct 1^d extends horizontally in or along the outer wall of the case for the entire length thereof and communicates at its opposite ends with fuel ducts 2^b in the opposite cylinders 2, 2, when the latter are properly attached to the crank case.

On the outer wall of crank case 1, adjacent the duct 1^d is a flattened boss 1^e in which is an opening 1^f communicating with the duct 1^d. To this boss 1^e is bolted one end of a short L-pipe casting 1^f, the other end of which is directly connected to the outlet of a carburetor C which may be of any suitable construction.

In the construction shown, the cylinders 2, 2, are attached to opposite ends of the crank case 1. The axes of said cylinders are parallel, but they are slightly displaced laterally to bring the cylinders into direct alignment with the respective related cranks on the shaft 1^b, as shown in Fig. 1.

Owing to this lateral relative displacement of the cylinders one end of the duct 1^d is deflected inwardly, as shown at 1^g in Fig. 1, and, for the purpose of lightness, the wall 90 of this part of the duct may be tubular and may be spaced from the adjacent interior corner of the casing 1 as shown at 1^h in Fig. 1.

Each cylinder 2 may be provided with a water jacket 2^a to prevent undue heating of its walls, and in or on one side wall of each cylinder 2, is a fuel duct 2^b which is preferably formed in casting the cylinder by using a suitable core. The duct 2^b extends parallel to the axis of the cylinder, and outside the water jacket 2^a, and is adapted to register at one end with the related end of the duct 1^d in the crank case 1, when the cylinder is attached thereto. The walls of the duct 2^b in each cylinder will be heated by the combustion of the gases in the cylinder, and consequently the fuel gases passing through such duct during the working of the engine will be heated thereby, thus in-

creasing the effectiveness of the fuel gases and also preventing condensation of such gases in said ducts.

To the outer end of each cylinder 2 is bolted a cylinder-head 3 which is formed with intake and exhaust ports respectively provided with valves 3^a and 3^b, which may be operated at the proper times by any suitable means, such means not forming part of the present invention.

10 The inlet duct 3^d in the cylinder head 3, is preferably formed in casting the head by using suitable cores. The outer end of the inlet duct 3^d is adapted to register with the outer end of the related duct 2^b in the cylinder to which the head is bolted. The inner end of duct 3^d connects with the inlet port.

15 A continuous fuel passage is thus formed by the communicating ducts 1^d, 2^b, 3^d in the walls of the crank case, cylinders, and cylinder heads, leading directly from the carburetor to the inlet valves of the cylinders; and the carburetor directly discharges through opening 1^e into the said fuel passage. By 20 this construction all outside manifolds are eliminated, and the fuel in the intake passage is sufficiently heated to prevent condensation thereof in the fuel ducts. In this construction the fuel gas intake passage has 25 no communication with the crank case but forms a continuous passage through the walls of the case, cylinders, and cylinder heads, to the point where it is admitted into the cylinders, such passage opening into the cylinders through the cylinder heads, and the crank case, cylinders, and cylinder heads 30 are required to carry and complete the intake passage.

Operation.

40 When an inlet valve 3^a is opened fuel gas will be drawn by the suction of the piston directly from the carburetor C through casting 1^f and opening 1^e into and through the fuel gas passage (formed by ducts 1^d, 2^b, 3^d) into the cylinder, the fuel gases being warmed and increasingly heated as they pass from the carburetor to the inlet valve. Any fuel gas trapped in the passage when the 45 inlet valve is closed will be heated by contact with the hot walls of said ducts. When the 50 exhaust valve 3^b is opened, the burnt gases are forced out of the cylinder through the exhaust ports 3^c at which time the inlet valve is closed.

55 The cycle of operations is as follows: On the instroke of either piston, its inlet valve 3^a in the duct 3^d in the cylinder head is opened, and fuel gas is drawn directly from the carburetor C, through the opening 1^e into the duct 1^d and thence through ducts 60 2^b and 3^d, into said cylinder. On the outstroke of such piston the inlet valve 3^a is closed and the charge compressed within the 65 cylinder, and when the piston reaches the

proper point the charge is fired; the resulting in stroke of the piston being its working stroke. On the next out stroke of the piston the exhaust valve 3^b is opened, and the burnt gases are expelled, thus completing the cycle of operations for that cylinder. The opposite cylinder goes through the same cycle, but the working stroke of its piston is arranged to occur during the intake stroke of the piston in the opposite cylinder, thus balancing the power impulses.

70 What I claim is:

1. In an engine of the character described; a crank case provided with a duct in and extending the length of one side wall thereof 80 but not communicating therewith, and having an opening in its side adapted to be connected with a carburetor; a cylinder attached to the said crank case and having a duct in its wall extending the length of the cylinder but not communicating therewith, and connected at its inner end with the adjacent end of the duct in the crank case; and a cylinder-head secured to the outer end of the cylinder and having an inlet port, 90 and a duct connecting with the said port and the outer end of the duct in the cylinder wall; the ducts in the crank case wall, cylinder, and cylinder-head, together forming a continuous passage whereby fuel gases 95 from the carburetor are conducted directly to the inlet port in the cylinder head, substantially as described.

2. In an engine of the character described; a crank case provided with a duct in and 100 extending along one side wall thereof but not communicating therewith, and having an opening adapted to be connected with a fuel supply; cylinders secured to opposite ends of said crank case; each cylinder having a 105 duct in its side wall extending the entire length of the cylinder but not communicating therewith and connected at its inner end with the edjacent end of the duct in the crank case; a cylinder head secured to the 110 outer end of each cylinder; each cylinder head being provided with an inlet port and a duct connecting said port with the outer end of the duct in the wall of the adjacent cylinder; said ducts in the crank case wall, 115 cylinders, and cylinder heads together forming continuous fuel passages whereby the fuel gases from the supply are conducted direct to the inlet ports in the cylinder heads, substantially as described.

3. An engine of the character described, having a crank case, cylinders attached to opposite ends of said case, and cylinder-heads attached to the outer ends of the cylinders; said crank case having a duct formed 125 in and extending along one side wall thereof but not communicating therewith and having an opening in its side adapted to be connected with a carburetor; each cylinder having a duct formed in its side wall ex- 130

tending the entire length of the cylinder but not communicating therewith, and connecting at its inner end with the adjacent end of the duct in the crank case; and each cylinder-head having an inlet port and a duct leading to the inlet port and having its outer end connecting with the outer end of the duct in the adjacent cylinder; the said several ducts together forming a continuous

fuel gas passage extending through the 10 walls of the crank case, cylinders and heads, whereby fuel gases are conducted direct from the carburetor to the inlet ports in the cylinder heads, substantially as described.

In testimony that I claim the foregoing as 15 my own, I affix my signature.

ANDREW W. AITKEN.
